CLAIM

The ornamental design for the EAS antenna, as shown and described.

DESCRIPTION

FIG. 1 is a front elevational view of an EAS antenna showing a first embodiment of my new design, the rear elevational view being a mirror image thereof;

FIG. 2 is an end elevational view of the left end thereof;

FIG. 3 is an end elevational view of the right end thereof;

FIG. 4 is a bottom plan view thereof; the top plan view being a mirror image thereof;

FIG. 5 is a front elevational view of an EAS antenna showing a second embodiment of my new design, the rear elevational view being a mirror image thereof;

FIG. 6 is an end elevational view of the left end of FIG. 5;

FIG. 7 is an end elevational view of the right end of FIG. 5; and,

FIG. 8 is a bottom plan view of FIG. 5; the top plan view being a mirror image thereof.

1 Claim, 2 Drawing Sheets

FIG. 1

FIG. 2

FIG.3

FIG. 4

FIG. 5

FIG. 6

FIG. 5 and FIG. 6 are identical.

FIG. 7

FIG. 7 is identical to FIG. 5.

FIG. 8

FIG. 8 is identical to FIG. 5.
